UNITED STATES PATENT OFFICE.

AUGUST H. MEINERS, OF ST. LOUIS, MISSOURI.

DESIGN FOR A STOP-VALVE BOX.

SPECIFICATION forming part of Design No. 33,787, dated December 25, 1900.

Application filed November 27, 1900. Serial No. 37,937. Term of patent 14 years.

To all whom it may concern:

Be it known that I, AUGUST H. MEINERS, of the city of St. Louis, State of Missouri, have invented and produced a new and original Design for a Stop-Valve Box, of which the following is a full, clear, and exact description, reference being had to the accompanying drawings, forming a part hereof.

Figure 1 is a perspective view showing my new design for a stop-valve box. Fig. 2 is a view looking into the box from below.

As shown in the drawings, the essential or material feature of my design consists of a box in the shape of a truncated pyramid, having flanges projecting laterally from the lower edges of its sides and having enlargements along the upper edges of the sides.

In the drawings, 1 denotes the box, which, as shown, is in the form of a truncated pyramid, and projecting from the lower edge of each side is a flange 2, and formed along the upper edges of the sides are enlargements 3. The inner side 4 of each side of the box is smooth and unobstructed from the bottom up to the top.

25
I claim—

The design for a stop-valve box, substantially as herein shown and described.

In testimony whereof I affix my signature in presence of two witnesses.

AUGUST H. MEINERS.

Witnesses:

ALFRED A. EICKS,
JOHN C. HIGDON.
